CLAIM

The ornamental design for a display screen with graphical user interface, as shown and described.

DESCRIPTION

FIG. 1 is a front view of a display screen with graphical user interface showing a first embodiment of my new design; and,

FIG. 2 is a front view of a display screen with graphical user interface showing a second embodiment of my new design. The dot-dash broken line showing a display screen illustrates the environment of the design and forms no part of the claim. The evenly-dashed broken lines illustrate portions of the graphical user interface that form no part of the claimed design.
